APPARATUS FOR MOUNTING THIN METALLIC FOIL ON CARRYING WEBS

Richard S. Reynolds, Richmond, Va.

Application May 12, 1943, Serial No. 486,722

7 Claims. (Cl. 154—37)

1

The present invention relates to the mounting of exceedingly thin metallic foil as, for example, aluminum foil, on carrying webs such as paper.

The thin aluminum foil mounted to both faces of a paper web provides a structure which has the appearance of a unitary foil structure and also substantially all of the advantages of the latter, i. e., a structure which is light-proof, moisture-proof, insect-proof, non-toxic, and non-tarnishing, and the structure possesses the unique lustrous surface of aluminum foil which imparts to printings, lacquerings and embossings brilliant effects unequalled by any other known printable material. However, it has heretofore been regarded as commercially impractical to mount foil thinner than approximately .0035" (approximately 30,000 square inches per pound) because the fragility of foil of lesser thickness causes frequent web breaks and interruptions to laminating operations by the foil mounting machine, and, hence, foil-cost factor plus the cost of an additional factor heretofore regarded as necessary, i. e., two separate operations in the mounting of the foil to both sides of a paper web—has limited the employment of such splendid protective material to the higher quality products in the field of packaging articles and substances which deteriorate when subjected to air, moisture, light or any one of said three conditions.

It is the specific object of the present invention to provide a method which will enable the mounting of exceedingly thin metallic foil, particularly aluminum foil, onto paper or other webs, and to provide apparatus for carrying out the method. Thus, by means of my method and apparatus, aluminum foil of a gauge down to .00012" (approximately 555 square feet per pound) may be mounted at high speed.

The characteristic of my method is the initial providing of a roll of foil consisting of at least two webs of foil placed face-to-face and wound together into the roll, and, in the mounting operation, the maintenance of the said two webs of foil in face-to-face relation, so that one will support the other, until one of the foil webs is adhered and supported by a paper or other web at which point the unadhered foil web continues to be supported not only by its associated foil web but by the paper until said second foil web receives its own support by adherence to the same or a second paper web; and, in this manner, the use of metallic foil, particularly aluminum foil, may be greatly extended. This follows because, first, the metal-cost factor is very substantially lower; and secondly, my method dispenses with

2

the cost of two separate operations for mounting foil to both sides of a web substance and provides a single operation. Further, in one phase of the invention, a single operation provides a roll of foil and paper webs united together in such manner that the foil lies at the opposite faces of the paper web and is bonded thereto, so that upon inspection the product appears as a unitary sheet of foil of a certain thickness, the thickness being determined by the gauge of the paper plus the foil gauge.

My method and apparatus will be described with reference to the accompanying drawings, in which:

15 Figure 1 is a view in elevation, partly in dotted lines, consisting of a vertical section through one form of apparatus for carrying my method into effect, the two webs of foil receiving adhesive, the apparatus being particularly adapted for hot melt adhesive.

20 Figure 2 is a fragmentary view, showing certain elements of the structure of Figure 1, but with the paper web so led that adhesive is applied to one side of the paper web, adhesive also being applied to one of the foil webs.

25 Figure 3 is a view similar to Figure 1, showing a modified form of machine and so constructed that suitable water-soluble adhesives can be applied to the outer surfaces of a double foil web.

30 Figure 4 is an enlarged fragmentary schematic view showing the manner in which the two foil webs are brought into adhesive contact with the opposite sides of a paper web being wound into roll form.

35 Figure 5 is a view similar to Figure 1, showing a further machine modification characterized by means for dipping the paper web into a hot melt or a certain type of cold adhesive and for carrying out the operation indicated by Figure 5.

40 Figure 6 is a view similar to Figure 4, showing the manner in which two foil webs are brought into adhesive contact with a paper web bearing adhesive on its opposite faces and being wound into roll form.

45 Figure 7 is a fragmentary plan view showing a web of paper, a web of foil lying on the same and intermediate adhesive, indicating by dotted and full lines the preferred side boundary positions for these elements.

50 Figure 8 is a view similar to Figure 7, showing the foil wider than the paper and its applied adhesive which is preferred when the adhesive is applied to the paper.

Figure 9 is an enlarged fragmentary side elevation showing more in detail the counterbal-

ance mechanism for relieving the gravitational effect of the wind-in roll.

Figure 10 is an enlarged fragmentary rear elevation of the structure shown in Figure 9.

In Figure 1 I have illustrated one section of a suitable frame 1 which is provided with a bearing support 1x for the shaft 2 of a roll of paper 3. The web of paper, indicated at p is led downwardly from its roll and partially around a heated drum 4, thence over a tension roller 5 to a surface rewind roller 6. This rewind roller is hollow and may be externally heated as by a gas flame impinging thereon from gas burner 7. It has a hollow shaft 8 appropriate for communication with the interior of the roller so that the roller may be internally cooled by water or other fluid. The paper web p leads to a rewinding roll 9, the latter being on a shaft 10 which may be mounted in two slide bearing blocks 11, the opposite sides of the blocks being channelled, in practice, so as to be received by the spaced supporting arms 12 of a bracket carried by frame 1.

The rewinding roll 9 is driven by the said surface rewind roller 6 and a companion surface rewind roller 6x of like construction. Each roller 6 and 6x carries a pinion indicated at 13 and 13x, driven by a gear 14.

In the structure of Figure 1 at least two foil webs, such as aluminum, are wound upon foil roll 15, the foil webs being in face-to-face relation. These foil webs are led over guide rollers 16, 16x and thence to adhesive transfer rollers 17, 17x, so that each of the foil webs receives adhesive on the outer face thereof. Adhesive transfer roll 17 receives adhesive from an intaglio knurled cylinder 18 which rotates in an adhesive fountain 19, the adhesive being controlled in thickness and width by the intaglio surface-area of the cylinder, aided by doctor 20 applied to the cylinder, as customary in gravure printing. Likewise, transfer roller 17x is in contact with an intaglio roller 21 in the adhesive bath of a fountain 22, the intaglio surface-area of cylinder 21 coating with a doctor 22 to control the width and thickness of a film of adhesive being transferred by transfer roller 17x.

After leaving the adhesive transfer rollers 17, 17x, the two webs of foil, each carrying a film of adhesive, meet smoothing spindles 23, which spindles rotate reversely to the direction of movement of the foil webs. The foil webs meet the paper web as it is being wound into roll formation, in the manner illustrated in Figure 4.

It will be understood with reference to Figure 1, that the adhesive transfer rollers 17, 17x may be offset one from the other so that each will have a "kiss" contact with the foil webs. The reason for this is that with the mutual positions of the said adhesive transfer rollers as shown in Figure 1, they should be driven at exactly the same speed as the rewind rollers 6 and 6x or be provided with a slip drive and the necessity for such precaution is eliminated when the said adhesive transfer rollers act together to impose traction upon the foil.

The manner in which the two foil webs are brought onto opposite faces of the paper web, by simultaneous or substantially simultaneous adherence thereto, is illustrated by the diagrammatic view, Figure 4. The paper web p is brought into contact with the adhesive face of foil web f slightly in advance of the time at which the adhesive-carrying foil web f' meets the opposite face of the paper web. This opposite face is presented to the adhesive-covered foil web f by the

turning of the paper and foil into convolutions upon the winding-in roller 9.

From the above it will be seen that the method and apparatus provide the laminating of foil upon a paper web and simultaneously on opposite faces of the paper web in the operation of winding in the laminated structure. This is an important feature of the invention because it greatly reduces handling of the foil as compared with customary methods, it greatly speeds up the laminating operation, it simplifies the laminating apparatus, and substantially reduces costs.

It will be understood that the winding in roll 9 may be counterbalanced in such manner that as its weight increases through the taking up thereon of the foil mounted web of paper the counterbalance effect will be correspondingly increased.

In Figure 1 a customary type of such counterbalance means is somewhat diagrammatically illustrated. To one or both of the bearing blocks 11 will be secured an upwardly extending rack 24 in mesh with a gear or gears 25 on a shaft 26 which carries one or a plurality of sprocket wheels 27 driving a weight carrying chain 28 in such manner that the weights are successively brought into counterbalancing relation to the winding in roll 9.

In Figure 2 the structure is substantially the same as that illustrated in Figure 1, but the paper web p is led by a guide roller 29 over the adhesive transfer roll 17x at which point it immediately receives and adheres the foil web f'. The two foil webs f and f' are maintained face-to-face and thus in mutual supporting relation until their support is augmented by the adherence of foil f' to one face of the paper web. The three webs, two foil and one paper, with the foil web f covered at its outer face with adhesive, reach the wind-in roll 9 and immediately foil web f is adhered to the opposite face of the paper web p as it is brought down in the convolution-forming action of roll 9, as will be understood by reference to Figure 4.

In all of the apparatus modifications, the principle of my method is employed. Each of the various forms of apparatus has its special advantages with respect more particularly to the type of adhesive employed and, incidentally, to an improvement in the mounting and counterbalancing of the winding-in roll.

In the structure of Figure 3, a suitable cold adhesive such, for example, as water-soluble adhesive, may be applied to the outer surfaces of the two foil webs, or, when desired, a hot melt coating may be applied to the outer surfaces of the foil webs or to one surface of the paper web. The length of travel of the paper web is increased to permit substantial dehydration of the web by heat treatment, the object of which is to substantially expel the water content and up to the point where further dehydration might impair the tensile strength of the paper, this expelled water being replaced by water of a water-soluble adhesive coating when employed.

In said Figure 3 the paper web p is led over a tension roller device 30, the tension being controlled by the position of the weight 31. The paper then passes over drying drums 32, 33 which may be heated by gas burners 34 or in any other suitable manner. The paper web then passes between two idler contact rollers 35, 36, the latter being maintained on a swing arm 37. At this point the upper surface of the paper web receives adhesive-coated foil web f'. The two foil webs f and f' are fed from a roll 38 on the frame 1 over idlers 39, 40 and 41, the last two rollers

being carried by a swing arm 42 which supports adhesive transfer roller 43 to which adhesive is applied by intaglio adhesive transfer cylinder 44 rotating in an adhesive bath contained in pan 45. A doctor 46 may control the thickness of the film on cylinder 44. By this means the web *f* receives adhesive, the two webs pass from a smoothing roller 47 to and between the rollers 35 and 36 having only "kiss" contact with the latter and then pass over an idler 48 and upwardly into contact with an adhesive transfer roller 49 which receives adhesive from intaglio adhesive cylinder 50 rotating in a bath of adhesive contained in pan 51. A doctor 52 may be applied to cylinder 50. Roller 49 is preferably mounted on a swing arm 49x. At this point the three webs are carried under a smoothing spindle 53 which smooths down the adhesive on foil web *f*. The three webs then pass over hollow temperature-controlled surface rewind roller 54 which acts in conjunction with temperature-controlled surface rewind roller 54x. The latter roller is positioned at a lower height than the former roller. These rollers carry pinions indicated by the dotted lines 55 in mesh with a drive gear 56 so that rollers 54, 54x are driven in clockwise direction.

The combined structure comprising three webs, i. e., a central web of paper and a foil web bonded to each of its opposite faces, is wound upon rewinding roll 9 by the action of the surface rewind rollers 54 and 54x in the manner indicated in Figure 4.

The mounting and counterbalancing of the rewind roll 9 is the same as that indicated in Figure 1, with the exception that the two sets of spaced arms 12, each of which receives between them one of the bearing blocks 11, are rearwardly inclined as is the customary pair of rack bars, one of which is shown at 57.

The surface rewind rollers 54, 54x are preferably hollow, as stated, and they may be heated by the gas flame elements 58 and internally cooled by circulating cold water admitted through their hollow shafts 59. These surface rewind rollers 54, 54x will be heated when a cold adhesive is employed so as to drive off water and hasten the drying of the adhesive. Also when hot melt is used, the heating of the said surface rewind rollers will serve to maintain the hot melt in suitable condition for adhesion preparatory to the bringing of foil *f* into contact with the convolutions of the paper web. The use of a flow of cooling water within the surface rewind rollers is to act as a control for the temperature. Also certain types of adhesive require instantaneous chilling and in such case cooling and not heating will be employed.

In Figure 5 each side of the paper web receives adhesive, preferably a hot melt adhesive, preliminary to the mounting operation. The paper roll 3 carried by frame 1xx has its web led over an idler 60 and a second idler 61 on the shaft of a wing arm 62 carrying at its free end a third idler 63 held in the adhesive bath of a heated pan 64. The heating may be effected by flowing hot oil or other fluid into and out of ports 64x in the pan from a suitable source of supply.

Immediately after receiving adhesive, such, for example, as hot melt (meaning any adhesive maintained in fluid condition by heat and including such adhesives as asphalt, resins, gums, wax, shellac-adhesive, and combinations thereof) the paper web *p* passes between a resilient surfaced pressure-roller 65 and a second roller 70

66, both being idlers. The paper web then passes over guide roller 67 and into register with a suitable heating device which, in the present instance, comprises two hollow trough-like members 68 which throw upon the opposite faces blasts of hot air, to condition the hot melt adhesive on the paper web. The two foil webs, *f* and *f'* pass from the foil roll 69 over idler rollers 70 which serve to smooth out the foil and thence to the hollow surface-rewind rollers 71 and 72, these rollers carrying pinions in mesh with a drive gear 74 for clockwise rotation of said surface rewind rollers.

In the operation of this apparatus, the two foil webs are successively adhered to the opposite faces of the paper web in the manner illustrated in Figure 6.

When the usual types of adhesive are applied to a web surface for adhering the same to a second web by pressure, lateral spreading movement of the adhesive is inevitable although such lateral extension of the adhesive may be slight. This spreading action generally is greater in the case of non-absorbent web such as foil than with absorbent web such as paper. In practicing my method the use of an intaglio knurled cylinder for transferring the adhesive satisfactorily confines the initial deposit area of the adhesive to that desired, and inasmuch as the degree of lateral adhesive spreading may be determined by certain factors, primarily the thickness of the film applied, I am able to so apply the adhesive that it will not spread beyond the edges of the paper and foil bonded web structure, and, at the same time, edge trimming can be eliminated altogether.

In Figure 7 the foil web *f* which will directly receive the adhesive has been partially stripped away from the paper web *p* to show the lateral boundaries of the adhesive, the latter being indicated by stippling at *a*. For clarity of illustration, foil web *f* is shown as slightly narrower than the paper web but in practice the widths may be the same. The adhesive *a* has been applied by the adhesive transfer roller in such manner that narrow marginal areas of the foil are free from adhesive. When the foil and paper webs are brought together under pressure, the predetermined spread of the adhesive will carry the same substantially to the edges of the structure without bleeding.

In Figure 8 the adhesive *a* will be applied to the opposite faces of the paper web *p* as, for example, in the manner illustrated in Figure 5, and thus entirely over the opposite faces of said paper web. The foil will be of slightly greater width than the paper, the slight excess width of the foil being predetermined in accordance with the known spread of the adhesive. This increased width of the foil may be controlled down to .32". When the three webs are brought together under pressure and are bonded by the adhesive, no trimming will be required.

With regard to the inclined mounting of the positioning of the rewinding roll 9 and its rewind rollers as shown in Figures 3 and 5 and the enlarged diagrammatic views, Figures 9 and 10, illustrate a convenient manner of ready release of the rewinding roll shaft 10. Inwardly projecting from each of the bearing blocks 11 is one-half of a shaft-receiving element which consists of member 11x (Figure 10) which is integral with member 11 and having a semi-annular recess for reception of shaft 10. Pivoted to member 10 at its base by means of pivot stud 75 is a strap block

76 having at its top an upwardly projecting stud 77 adapted to enter the aperture of a latch arm 78 pivoted at 79 upon member 112. It will be understood that this arrangement will be employed at each end of the shaft.

When the rewinding roll 9 is ready to be removed from its position in full lines, Figure 9, the latches 76 will be raised, whereupon strap blocks 76 will drop and the rewinding roll with its shaft will move by gravity from its position in full lines to its position on table 80 as indicated by the dotted lines of that figure. The roll may then be transferred to a truck most conveniently and with a minimum of effort. Thereupon rack 57 and the bearing blocks may be restored to initial position by rotating the hand wheel 81, Figure 9.

By my method a single element, to wit, the rewind roll, serves (a) to draw the webs without the necessity of controls; (b) mount the webs; (c) heat or cool the webs; and, (d) rewind the webs.

Reference has been made above to the use of cold adhesive, one type being water-soluble adhesive. My method includes means for overcoming a serious obstacle in the use of such adhesive, which obstacle is presented because the final structure is such that the adhesive is sealed in by the foil webs and cannot escape. I have found that under a relative humidity of 50-55 the moisture content of average paper webs ranges from 6-8%. In my method the paper web (or webs) in travel to the foil web is so treated as to reduce the moisture content in a degree per square foot substantially equivalent to the moisture content of a film of adhesive on such area. Thus when the paper web (or webs) meets the foil with a film of adhesive between them, and the one or the other of the surfaces, the paper immediately begins the process of absorption of water. However, due to the high speed of movement of the webs, this absorption does not affect the adhesion, and during the rewind operation, or shortly subsequent thereto, the paper web is restored to its normal water content, taken from the adhesive, and, at the same time, the adhesive is dehydrated to the extent that it performs its normal bonding function. To further assist in this operation, the rewind rollers are under temperature control, i. e., being either heated or cooled, as conditions require.

It will be further seen that there is no possibility of lack of synchronism between the wind-in roll and various rotary elements intermediate to roll and roll of foil webs. All of these intermediate rotary members may be idlers and these idlers, light in character, are, wherever necessary, supported by ball-bearings or roller-bearings.

The intaglio adhesive cylinders 18, 21, 44 and 59, may be positively driven without affecting the synchronism just described since the adhesive transfer rollers may be idlers having light contact with the intaglio cylinders.

Having described my invention, what I claim and desire to secure by Letters Patent, is as follows:

1. In an apparatus for laminating webs of foil and carrying web, a carrier roll for two webs of foil arranged face to face, a carrier roll for a carrying web, means for rewinding a roll of laminated foil and carrying web, guide means for the two-web foil and the carrying web disposed intermediate the carrier rolls and the rewinding roll, guide means for guiding the carrying web into

initial engagement with one web of the foil only, means for applying adhesive to each face of the two-web foil, the means for applying adhesive to the foil face initially to be united with the carrying web being disposed along the path of the moving foil ahead of the place of initial engagement between the carrying web and the foil, the rewinding roll being adapted to receive the two-web foil with the carrying web adhered to one face thereof and, upon its rotation, to bring the other face of the two-web foil into contact with the carrying web.

2. In an apparatus for laminating webs of foil and carrying web constructed in accordance with claim 1, two surface rewind rollers for rotation and support of the rewinding roller, means for heating the surface rewind rollers and means for circulating a cooling fluid internally of the surface rewind rollers.

3. In an apparatus for laminating webs of foil and paper, a carrier roll for two webs of foil arranged face to face, a carrier roll for a web of paper, a rewinding roll, at least one surface rewind roller for rotating the rewinding roll, a shaft carrying said rewinding roll, two bearing blocks for receiving said shaft, a set of rearwardly inclined spaced arms for receiving said bearing blocks, strap blocks pivoted to said shaft, means to latch said strap blocks to said bearing blocks, the strap blocks being adapted to drop upon release of said latching means and a table having a receiving surface disposed at a height below the top of the rewind roller and adapted to receive the rewinding roll after release of said latching means.

4. In an apparatus for laminating webs of foil and a carrying web, a carrier roll for two webs of foil arranged face-to-face, a carrier roll for a carrying web, means for rewinding a roll of laminated foil and carrying web, guide means for the two-web foil and the carrying web disposed intermediate the carrier rolls and the rewinding roll, guide means for guiding the carrying web into initial engagement with one web of the foil only, means for applying adhesive to each face of the carrying web, the means for applying adhesive to the carrying web being disposed along the path of the moving carrying web ahead of the place of initial engagement between the carrying web and the foil, the rewinding roll being adapted to receive the two-web foil with the carrying web adhered to one face thereof, and, upon its rotation, to bring the other face of the two-web foil into contact with the carrying web.

5. In an apparatus for laminating webs of foil and a carrying web, a carrier roll for two webs of foil arranged face-to-face, a carrier roll for a carrying web, means for rewinding a roll of laminated foil and carrying web, guide means for the two-web foil and the carrying web disposed intermediate the carrier rolls and the rewinding roll, guide means for guiding the carrying web into initial engagement with one web of the foil only, means for applying adhesive to one face of the two-web foil, means for applying adhesive to one face of the carrying web, one of said means for applying adhesive being disposed along the path of the moving carrying web ahead of the place of initial engagement between the carrying web and the foil, the rewinding roll being adapted to receive the two-web foil with the carrying web adhered to one face thereof and, upon its rotation, to bring the other face of the two-web foil into contact with the carrying web.

6. In an apparatus for laminating webs of foil

and carrying web, a carrier roll for two webs of foil arranged face to face, a carrier roll for a carrying web, means for rewinding a roll of laminated foil and carrying web, guide means for the two-web foil and the carrying web disposed intermediate the carrier rolls and the rewinding roll, guide means for guiding the carrying web into initial engagement with one web of the foil only, means for applying adhesive initially to one face of the carrying web, and means for applying adhesive to the face of the two-web foil opposite the face to be united initially with the carrying web, the means for applying adhesive to said one face of the carrying web being disposed along the path of its movement ahead of the place of initial engagement between the carrying web and the foil, the rewinding roll being adapted to rewind the two-web foil with the carrying web adhered to one face thereof and, upon its rotation, to bring the other face of the two-web foil into contact with the other face of the carrying web.

7. In an apparatus for laminating webs of foil and a carrying web, a carrier roll for two webs of foil arranged face to face, a carrier roll for the carrying web, means for rewinding a roll of laminated foil and carrying web, guide means for the two-web foil and the carrying web disposed intermediate the carrier rolls and the rewinding roll, said guide means including means for guiding the carrying web into initial engagement with one web of the foil only, means for applying adhesive to at least one of the webs to adhesively bond one web of foil to one face of the carrying web on initial contact, the means for applying adhesive
